UNITED STATES PATENT OFFICE.

FREDERICK W. HEDGELAND, OF CHICAGO, ILLINOIS, ASSIGNOR TO THE W. W. KIMBALL COMPANY, OF SAME PLACE.

MUSIC-RACK FOR PIANOS OR ORGANS.

SPECIFICATION forming part of Letters Patent No. 595,710, dated December 21, 1897.

Application filed September 25, 1897. Serial No. 652,966. (No model.)

To all whom it may concern:

Be it known that I, FREDERICK W. HEDGELAND, a citizen of the United States, residing in Chicago, in the county of Cook and State 5 of Illinois, have invented a new and useful Improvement in Music-Racks for Pianos or Organs, of which the following is a specification.

This invention relates to certain improvements in the music-racks of organs and pianos, and has been devised more especially for use in self-playing instruments.

One object I have had in view in the invention has been to make it possible to give 10 the case of a self-playing piano or organ the same appearance and form as the cases of the ordinary non-self-playing instruments, so that the addition to the instrument of the self-playing mechanism does not disfigure the 15 case in any way nor give external notice of its own presence in the instrument.

Another object in view has been to provide a convenient construction whereby the music-rack may be made to normally conceal the 20 music-sheet of the self-playing mechanism and yet be itself movable into the case of the instrument, so as to uncover the music-sheet and present a finished front when thus disposed of.

25 The nature of the invention is fully disclosed in the accompanying drawings, wherein—

Figure 1 is a partial front view of the instrument-case. Fig. 2 is a back view of the 30 music-rack. Figs. 3 and 4 are vertical sections of the case and music-rack, showing the latter in different positions.

In said drawings, A represents the front of the instrument-case, and B a disappearing 35 music-rack. The latter is adapted not only to be swung out at the bottom to position it for holding music books or sheets while the instrument is being played manually, but it is also movable bodily into the case. It is 40 hinged at the top to the horizontal part of a swinging U-shaped wire frame C, the lower ends of the limbs of which are stationarily pivoted at C'. This permits it to be swung 45 out at the bottom, as indicated by dotted lines at Fig. 3, into the position to which it is moved for manual playing, and it is held

in this position by the limbs of another U-shaped wire frame D, hinged to the back of the rack and having a spring or springs D', whereby to throw said limbs down and into 50 action as soon as the rack has been swung far enough away from the case. The manner of hinging described also allows the bottom of the rack to be swung up until the rack reaches a horizontal position, so it can then 55 be pushed into the case, as will be understood from Fig. 4, an open space being provided in the case to receive the rack. In this latter position the upper end of the rack is supported by the frame C, and the ledge B' 60 of the rack stands flush with the front of the case and closes the opening through which the rack enters the case. As the bottom of the ledge B', which is now presented to view, may be nicely finished, the good appearance 65 of the instrument is not injured by raising the rack to this position, and the opening in the case is effectually concealed by the ledge when the rack is raised and by the rack itself when down.

Immediately behind the rack is a chamber 70 E, in which is located the rolls F and G, supporting and operating the perforated music-sheet H, and J is the tracker-range, these 75 parts belonging to the self-playing mechanism. Access is gained to this chamber and the music-sheet is brought into view by raising the rack, as before described, and this is done whenever the instrument is to be played 80 automatically.

I claim—

1. The musical instrument having a disappearing music-rack hinged at its top to a swinging frame and movable into the case in a horizontal direction, substantially as specified.

2. The musical instrument having a disappearing music-rack hinged at its top to a swinging frame and movable into the case in a horizontal direction, said rack also having 95 a ledge adapted to close the opening through which the rack enters the case, substantially as specified.

3. The combination in a self-playing instrument of a disappearing music-rack and a 100 traveling music-sheet, said music-sheet being concealed by the rack when the latter is

normally positioned, and the rack being movable into the case above the sheet, substantially as specified.

4. The combination in a self-playing instrument, of a disappearing music-rack hinged so it may be swung into a horizontal position and be then pushed into the case, said rack also having a ledge B' acting to close the

opening in the case, and a traveling music-sheet normally concealed by the rack and exposed by raising the rack, substantially as specified. 10

FREDERICK W. HEDGELAND.
